(57) **CLAIM**

The ornamental design for a grounded electrode for a plasma processing apparatus, as shown and described.

DESCRIPTION

FIG. 1 is a front, top and right side perspective view of a grounded electrode for a plasma processing apparatus according to the design;

FIG. 2 is a rear, bottom and left side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a cross-sectional view taken along line 9-9 of FIG. 7; and,

FIG. 10 is an enlarged view of the portion shown in BOX 10 in FIG. 9.

The broken lines show the boundary of enlarged portions and form no part of the claimed design.
